(57) **CLAIM**

The ornamental design for medical tweezers, as shown and described.

DESCRIPTION

1.-2. Medical tweezers

Figure 1.1 is a top view of a medical tweezers;

Figure 1.2 is a front view thereof;

Figure 1.3 is a bottom view thereof;

Figure 1.4 is a right view thereof;

Figure 1.5 is a left view thereof; and

Figure 1.6 is an enlarged perspective view of a portion of the medical tweezers.

The present articles are medical (surgical) tweezers used for treatment of an acne such as a comedo; portions shown by solid lines are intended to obtain a design registration as a partial design.
